UNITED STATES PATENT OFFICE.

ARTHUR PESTEL, OF NEW YORK, N. Y.

TAPPING MACHINE.

Application filed March 25, 1918. Serial No. 224,520.

To all whom it may concern:

Be it known that I, ARTHUR PESTEL, a citizen of the United States, residing at 557 West 124th Street, in the State, county, and city of New York, have invented a new and useful Tapping Machine, of which the following is a specification.

My invention relates to improvements in tapping machines and has as one of its objects, the provision of a machine that can be placed in a horizontal, vertical or any other desired intermediate position to perform the tapping operation.

Another object, and one of the most important, is the provision of an efficient, yet exceedingly simple and effective lubricating system, the arrangement of which insures the exclusion of oil from between the friction surfaces of the tap drive.

A further object is the provision of a hand tapping arrangement that can be used on large work.

A still further object is the provision of a belt tightener that can be operated regardless of the position the tapping machine is in.

The objects are obtained by the mechanism of which the following is a description and which is illustrated in the accompanying drawings in which—

Figure 1 is a sectional front view, the section being taken at A—A, Figure 3, looking in direction of arrows.

Figure 2 is a side elevation of Figure 1.

Figure 3 is a plan view.

Figure 4 is an illustration showing the tapping arrangement placed in its extreme positions.

Figure 5 illustrates the belt tightening device in a section taken at B—B Figure 3.

Figure 6 shows the idler pulley and its lubricating arrangement in sections.

Figure 7 is a plan view of the work table and the table guide.

Figure 8 illustrates in a section the locking arrangement of the table and table guide.

Figure 9 is a plan view of the adjustable table support and its operating mechanism.

Figure 10 is a modification of Figure 1, illustrating a different construction of the tapping mechanism.

Figure 11 illustrates the hand tapping rod.

Like reference letters refer to like parts throughout the several views.

My tapping machine consists of a hollow spindle 1, both ends of which are turned off and run in bearing bushings 2 and 3, Figure 1. A chuck in form of a clamp or other suitable device 4 is fastened to the lower end 5 of spindle 1 by means of a screw 6. In order to obtain the clamping effect, part 4 is provided with a vertical slot 7, Figure 2, and a horizontal slot 8, Figures 1 and 2. This clamp 4 has at its lower end a threaded projection 9 which is engaged by a tapholder 10 into which the tap 11 is soldered, driven, or otherwise secured.

It will be seen, that the chuck thus described is of especially light design, which is quite necessary when taps of small diameter are used. When suddenly stopped, the impact of a heavy chuck, on account of its mass, will turn the spindle a short distance further and is therefore more liable to break the tap.

In order to give the tap 11 the required forward and reverse motion when tapping work, the spindle 1 carries a friction member 12. This friction member consists of a perforated steel plate 13 which is riveted to a collar 14, which in turn rests on a shoulder 15 of spindle 1 and is preferably shrunk on, riveted on, or otherwise held in place by suitable means. The steel plate 13 carries at its upper and lower surfaces friction discs 16, preferably made of leather or some other kind of material with a high friction coefficient. In order to secure the friction discs 16, the perforations 17 in the steel plate 13, Figure 3, are filled out with small leather pads 18, Figure 1, to which the discs 16 are glued.

The friction member 12 is situated between two in opposite directions revolving friction blocks 19 and 20. These friction blocks are preferably made of hard wood, it is, however, understood that they could be made of any other friction-producing material, or specially prepared surfaces. The friction blocks 19 and 20 are carried by rope pulleys 21 and 22 to which they are fastened by means of screws 23. Rope pulleys 21 and 22 revolve on the stationary bushings 2 and 3 which are provided with shoulders 24 and 25 which serve for holding the pulleys in place. The bushings 2

and 3 are located in bearings 26 and 27 of the support 28 and are securely clamped in these bearings by means of bearing caps 29 and 30 and screws 31, Figure 2. The support 28 is J-shaped and the bearings 26 and 27 are located in the ends of the horizontal arms 32 and 33. The opposite ends of the arms 32 and 33 form bearings 34 and 35, which engage rod 36, which is held in place by a set screw 150. The work table 37 is clamped to rod 36 which also connects the tapping arrangement to the swivelhead 38 by means of ears 39 and 40, Figure 2, thereby forming one complete unit of the tapping mechanism and the work table. These ears 39 and 40 are cast in one piece with the swivelhead 38 and are made so as to fit between the bearings 34 and 35 of support 28. By means of the swivelhead 38 the tapping mechanism may be placed in either a horizontal, vertical, or any other desired intermediate position, Figure 4. For this purpose the swivelhead 38 is pivoted on the head 41 of the main drive bushing 42, which is screwed to the base plate 43 by means of screws 44. A shoulder 45 on the main drive bushing 42 serves for holding the swivelhead 38 in place and against a projection 46 of the base plate 43, Figure 3. There is, of course, sufficient play between shoulder 45 and projection 46 to allow an easy movement of the swivelhead. In order to be able to lock the tapping mechanism in the desired position a semicircular slot 47 is provided on the swivelhead 38, Figure 1, through which a threaded bolt 48 passes which engages in a correspondingly threaded hole 49, located in an extension 50 of the base plate 43, Figure 3. A washer 51 is advantageously placed underneath the head of the bolt 48. To swing the tapping arrangement into the desired position bolt 48 is loosened and after the desired position is obtained again tightened. The drive of the tapping mechanism is illustrated in Figure 3. A shaft 52 is driven in the direction indicated by the arrows by a pulley 53, or by a motor directly connected to the motor shaft in any well known manner. Shaft 52 carries on its other end a rope pulley 54. Power is transmitted to the rope pulleys 21 and 22 by means of a belt 55 which runs over an idler pulley 56. By this arrangement the rope pulleys 21 and 22 are driven in opposite directions, pulley 21 rotating in a clockwise, and pulley 22 in a counterclockwise direction. The idler pulley is loosely held in place between two arms 57 and 58 of the swivelhead 38 by means of a bracket 59, to which the pulley 56 is attached by means of a shoulder bolt 60 and nut 61, Figure 6. The bracket 59 has pivots 62 and 63 on which it swings in openings 64 and 65 of the arms 57 and 58. Opening 64 is shaped

as shown in Figure 3, so as to permit the bracket 59 with idler pulley 56 to be put in place.

In order to insure satisfactory lubrication of the running surface 66, Figure 6, of the idler pulley 56 bolt 60 contains a chamber 67 which is filled with grease or other suitable lubricant and which is kept closed by means of a threaded plug 68. The lubricant reaches the running surface 66 through holes 69 through which it may be forced by turning the plug 68.

To facilitate the location and tapping of work a table 37 is provided, Figure 2. The work is placed either on the upper or lower surface of table 37 depending on the shape and kind of work to be tapped. After locating the work on the table in such a way that the hole to be tapped is directly over a slot 70 in table 37 the table is moved up toward the tap 11 until the tap enters the work. A slight upward pressure is exerted on the work until tap 11 passes through it and into the slot 70. The table and work are then pressed downward which action 90 will reverse the tap and disengage it from the work. The forward and reverse motion of the tap is obtained through the friction member 12 on tap spindle 1, which is situated between the friction blocks 19 and 20 95 which revolve in opposite directions. The distance between these two blocks is somewhat larger than the thickness of the friction member 12, thereby forming a space 71, Figures 1 and 2, sufficient to allow the friction member to be moved up and down and to be engaged and disengaged with either of the friction blocks 19 and 20. 100

The table 37 is supported on a table rod 72 which slides in two bearings 73 and 74 of the support 75, Figures 1, 2, and 9, which is adjustably clamped to rod 36, with its slotted bearing 76. To facilitate the clamping and adjustment of the height of table 37 a threaded bolt 77 is securely fastened in boss 78 of table support 75 and passes through a hole 79 of boss 80. By loosening and tightening the handle 81 the table support 75 with table 37 may be adjusted in any desired position on rod 36. In order to give the 115 table 37 sufficient rigidity while being moved up and down a guide 82 is provided, Figures 1, 2, 7 and 8, the fork 83 of which slides on rod 36. This guide is clamped to the collar 84 by screw 86, which partially engages in a 120 groove 87 of collar 84, Figure 8. Through this arrangement the table 37 with slot 70 are held securely in the required position after having been adjusted. To limit the motion of the table 37 while tapping, a stop 125 collar 88 with set screw 89 is provided on table rod 72. Table 37 may be operated either by hand, a treadle and lever such as shown in Figures 2 and 9, or by any other suitable device the construction of which 130

may be varied to meet different requirements. In the device illustrated in the drawing a lever 151, Figures 2 and 9 is pivoted on bolt 77 and is formed to a fork 152 which 5 engages collar 88 on table rod 72. A chain 153 is connected to the end of lever 151 which is fastened to a suitably located treadle (not shown on drawing) for foot operation.

10 Special attention had to be given to the lubricating system in order to secure perfect lubrication of the different bearings while the machine is running in a vertical or horizontal position. At the same time care had 15 to be taken to prevent oil from reaching the friction surfaces 16 of the friction member 12 as this would materially decrease the working efficiency of the machine. For this purpose oil cups 90 and 91 are provided on 20 the friction member 12, which catch the oil emerging from between the bushing 2 and the hub 92 of pulley 21. The lubricant is brought to the running surface of hub 92 from a reservoir 93 in bushing 2 through a 25 passage 94, and in order to guide the superfluous oil into the oil cup 90 a guide 95 located between the hub 92 and block 19 which reaches with its end into cup 90, thereby preventing oil from creeping along the inner 30 walls of block 19 and reaching the friction surfaces. The end of guide 95 is advantageously flared so as to insure a throwing off of the oil against the inner walls of cup 90 through the action of the centrifugal 35 force, while the machine is running. From the cup 90 the oil is drained through holes 96 and guided into the reservoirs 97 by means of cup 91 which is also flared out for the same reason as guide 95. The lubrication 40 of the running surface of hub 98 of pulley 21 is obtained by draining the oil in reservoir 97 through a number of slots 99 in hub 98. In order to lubricate the spindle bearing 100, a hole 101 is drilled through bushing 3 45 through which oil passes to said running surface. To insure perfect lubrication of the hubs 92 and 98 the bushings 2 and 3 may have helical oil grooves cut into their surfaces. When the machine is running in a 50 horizontal position oil is supplied to the bearings by conveniently located oil holes 102. Any oil that should emerge from the running surface would be guided into the reservoirs 97 and 103 formed by the blocks 55 19 and 20 from which any accumulating oil would be thrown off through tubes 104. The amount of oil, however, which would reach the reservoirs, while the machine is running in a horizontal position is negligible, as the 60 oil would have a tendency to stay in the bearings, therefore the oil thrown off through the tubes 104 would not interfere with the operation of the machine.

It is, at times, necessary to tighten belt 55, 65 and in order to do this without loss of time

and without having to resort to the ordinary and troublesome means of shortening the belt the arrangement described in the following is provided. The swivelhead 38 has two lugs 104 and 105, Figure 5. A threaded bolt 106 passes through lug 104 and rests with its rounded end 107 against a bolster 108 of arm 32. Another threaded bolt 109 passes through an opening 110 in arm 33 and engages lug 105 of the swivelhead 37. A 70 partially rounded washer 111 is placed under the head of bolt 109, the purpose of which will be explained presently. Should it be required to tighten the belt 55 bolt 109 is first loosened, by which action the support 75 28 is free to swing in its bearings 34 and 35 on rod 36. The slack in the belt is then taken up by turning bolt 106 until the belt is sufficiently tightened. The support 28 is then again rigidly secured by tightening bolt 80 109, the washer 110 adjusting itself to the displaced position of the support and holding it firmly, thereby practically forming one unit with the swivelhead 38. The herewith described belt tightening arrangement 85 90 will also prevent damage to the machine and work, as well as injury to the operator, as none of the parts is able to move from its occupied position in case the belt should break. It is, of course, understood that 95 above belt tightening arrangement may be left out and that support 28 and swivelhead 38 may be made in one piece if so desired.

In certain work, especially when tapping large sized holes and where the machine 100 may not have been made large enough for tapping such holes with power, it may be desirable to do the tapping by hand or by means of a hand tapping machine, and therefore provisions were made on the machine 105 described on the preceding pages to change the machine from a power tapping machine to a hand tapping machine. In order to obtain this condition clamp 4 with tap holder 10 and tap 11 are removed and a rod 112, 110 Figure 11, with a crank 113 put through the hollow of the spindle 1. The crank 113 is adjustable in the head 114 of rod 112 to accommodate the tapping of large and small 115 holes, and can be secured in the desired position by set screw 115. Tap holder 10 with tap 11 are then screwed onto the threaded extension 116 of rod 112.

When this arrangement is used it is not necessary to bring the work against the tap, 120 therefore it is desirable to have the table 37 stationary. For this purpose the bearing 73 is formed as a clamp by means of which table 37 may be secured. The bearing 73 is split as shown at 117, Figure 9, a threaded 125 bolt 118 with handle 119 is provided to operate the clamp.

Figure 10 is a modification of Figure 1, the principle of which is the same and only differs constructively. 130

The object of this construction is to simplify the oiling system which is obtained by designing the driving pulleys, and friction blocks as well as the oil cups somewhat differently from the ones previously described. As will be seen, the webs of the pulleys and the friction blocks are developed in such a way that they form reservoirs for superfluous oil emerging from between the bearings.

The hollow spindle 120 runs in stationary bushings 121 and 122 which are rigidly held in place by bearing caps 123 and 124 on the I-shaped support 125, the same as previously described. The friction member 126 is built up similar to the one explained in Figure 1 and is riveted to a collar 128 on spindle 120. The friction member is actuated by friction blocks 129 and 130, which run in opposite directions and which are fastened to the rope pulleys 131 and 132 by means of screws 133 and rotate on the bushings 121 and 122. The rope pulleys 131 and 132 are driven in the same manner as the pulleys shown in Figures 1 and 2.

As in Figure 1 the lubricating oil is placed in a similar constructed oil well 134 from where it is brought to the running surface 135 of bushing 121 through a passage 136 and evenly distributed over the entire running surface by means of helical oil grooves 137. The overflow of the oil emerges at 138 and is prevented from reaching the friction surfaces of the driving member 126 by an oil guard 127 which is fastened to the before mentioned friction member. The oil thus caught in cup 127 is drained off through holes 139 in the bottom of the cup and collar 128. An oil cup 140, similar to 127, is provided on the lower surface of the collar, which prevents the oil from being thrown onto the friction surfaces and guides it into reservoir 141 of the pulley 132. In order to lubricate the running surface of hub 142 of pulley 132 oil is drawn from this reservoir through a passage 143 and is distributed over the running surface by means of helical grooves 144 and 145. Oil is delivered through passage 143 to the running surface somewhat below the collar 146 of bushing 122 and as the tendency of the oil would be to flow toward the lower end of said bushing when running in a horizontal position, the oil grooves 144 and 145 are arranged in such a manner that their ends are in line with passage 143. Through this arrangement positive lubrication of the part of the bushing above passage 143 as well as of the part below is assured. Oil groove 145 is connected with a passage 147 in bushing 122 to which oil is carried to the lower bearing of spindle 120. When the machine is running in a horizontal position the oil will tend to remain in the bearings and no oil or very little will emerge from between the

shoulders of the bushings 122 and 123 and the hubs of the pulleys 131 and 132. Should there, however, be an overflow of oil, it would be caught in the cups 138 and 140 and thrown off into the reservoirs 141 and 148 for which purpose the ends of the cups are flared out. As the oil is thrown off the flares of cups 138 and 140 it is caught in a recess 149 of friction blocks 129 and 130 which is shaped so that the oil will easily flow into reservoirs 141 and 148. If it should be found advisable said reservoirs could be provided with drains similar to the draining tubes 104, Figure 1, by means of which an excessive accumulation of oil would be prevented.

I do not wish to limit myself to any particular construction of friction members and surfaces, means for preventing the oil from reaching said friction surfaces, for swinging, adjusting, operating or driving of the herein described tapping machine, as it will be obvious that the construction may be varied considerably without departing from the spirit of my invention as set forth in the claims.

Having now particularly described and ascertained the nature of my said invention and in what manner the same is to be performed I declare now that what I claim is:

1. In a machine of the character described, a mounting, a swivel-head supported by said mounting, a pivoted support carried by said swivel-head, bushings fixed in said support, one of said bushings being formed to provide encircling passageways for the conduction of a lubricant, a rotating and axially movable spindle mounted in said bushings, a friction drive consisting of two oppositely driven members mounted on said bushings, friction surfaces on said members, a friction disc fixed to said spindle and adapted to engage said friction surfaces, a threading tap carried on one end of said spindle, a rod carried by said swivel-head, an adjustable support mounted on said rod, an axially movable table carried by said support, a lever pivoted on said support and engaging said table, and means on said table for limiting the axial movement thereof.

2. In a machine of the character described, a mounting, a rotatable swivel-head supported by said mounting, means to lock said swivel-head to said mounting in any position within a swing of 180° , a rod carried by said swivel-head, an adjustable table support mounted on said rod, an axially movable table rod carried by said support, a table fixed on one end of said table rod, a collar on said table rod for limiting the movement thereof, and a lever having pivotal connection with said table support and engaging said collar.

3. In a machine of the character de-

scribed, a mounting, a rotatable swivel-head supported by said mounting, means to lock said swivel-head to said mounting in any position within a swing of 180° , a rod 5 carried by said swivel-head, an adjustable table support mounted on said rod, a table carried by said support, and means for moving said table in relation to said support.

10 4. In a machine of the character described, a mounting, a rotatable swivel-head supported by said mounting, a threading mechanism mounted on said swivel-head, a rod carried by said swivel-head, a table support 15 carried by said rod, a table mounted on said support, and a guide fastened to said table and engaging said rod.

5. In a machine of the character described, a mounting, a swivel-head movable 20 on said mounting, a spindle carried by said swivel-head, a threading tap fixed at one end of said spindle, an extension mounted on said swivel-head, a support carried by said extension, an axially moveable table 25 mounted in said support and means pivoted on said support for actuating said table.

6. In a machine of the character described, a mounting, a swivel-head moveable on said mounting, a spindle rotatable in 30 two directions by said swivelhead, an extension on said swivel-head, a support carried by said extension, a moveable table mounted in said support and means carried by said support for actuating said table.

35 7. In a machine of the character described, a spindle, a friction drive consisting of two oppositely driven members revolvably mounted on said spindle, friction surfaces on said members, a friction disc 40 mounted on said spindle and adapted to rotate between said friction surfaces, oil cups on said friction disc and an oil guide mounted on one of said driven members and extending into one of said oil cups.

45 8. In a machine of the character described, a revolvable and axially movable spindle, a friction drive consisting of two oppositely driven members, friction surfaces on said members, a friction disc mounted on said spindle and adapted to engage said friction surfaces, oil cups on said friction disc and an oil guide, having an outwardly flared edge, mounted on one of said driven members.

55 9. In a machine of the character described, a spindle, a friction drive consisting of two oppositely driven members revolvably mounted on said spindle, friction surfaces on said members, a friction disc 60 mounted on said spindle and adapted to rotate between said friction surfaces, oil cups on said friction disc and an oil guide mounted on one of said driven members.

10. In a machine of the character described, a spindle, a friction drive consisting

of oppositely driven members, a friction disc mounted on said spindle and adapted to engage said friction surfaces, oil cups on said friction disc and an oil guide mounted on one of said driven members.

70 11. In a machine of the character described, a spindle, a friction drive consisting of two reversely rotating driven members, friction surfaces on said members, a friction disc mounted on said spindle and adapted to engage said friction surfaces, oil cups mounted on said friction disc and a passageway connecting said oil cups formed in said friction disc.

75 12. In a machine of the character described, a revolvable and axially movable spindle, a friction drive revolvable on said spindle and comprising two oppositely driven pulleys, friction blocks mounted on said driven pulleys, friction surfaces on said 80 friction blocks, a friction disc mounted on said spindle and adapted to revolve between said friction surfaces, oil cups mounted on said friction disc, and an oil guide mounted 85 on one of said friction blocks.

90 13. In a machine of the character described, a spindle, a friction drive mounted on said spindle and comprising friction members, friction surfaces on said members, a friction disc mounted on said spindle and 95 adapted to engage the surfaces of said members; and oil cups mounted on said friction disc, the latter being formed to provide a passageway between said oil cups.

100 14. In a machine of the character described, a friction drive consisting of two reversely rotatable members, friction blocks having friction surfaces mounted thereon, said friction blocks being constructed so as to form reservoirs on the side opposite their 105 friction surfaces, a spindle, a friction disc mounted on said spindle, and oil cups mounted on said friction disc.

110 15. In a machine of the character described, an adjustably mounted support, a spindle mounted therein, a threading mechanism mounted on one end of said spindle, a friction drive mounted on said spindle and consisting of two reversely rotatable members, friction surfaces on said members, a 115 friction disc adapted to engage said friction surfaces, and oil cups mounted on said friction disc.

120 16. In a machine of the character described, a moveable support, means to lock the support in any desired position, a spindle mounted in said support a threading mechanism mounted on one end of said spindle, a friction drive mounted on said spindle and consisting of two reversely rotatable 125 members, friction surfaces on said members, a friction disc mounted on said spindle and rotatable between said friction surfaces, oil cups on said disc and an oil guide mounted on one of said members.

17. In a machine of the character described, an adjustable pivoted support, a spindle mounted on said support, a friction drive consisting of two driven pulleys mounted on said spindle, a driving pulley mounted in a fixed bearing, an idler pulley mounted in a self-adjusting support, suitable belting to operate said driven pulleys in opposite directions through the medium of said idler pulley, and means for adjusting the tension on said belting.

18. In a machine of the character described, a spindle, a friction drive consisting of two reversely rotating members, friction surfaces on said members, a friction member engaging said surfaces, said friction member comprising; a perforated plate, said perforations containing a plurality of pads of light material, discs of material having a high frictional coefficient, fixed on either side of said plate and engaging said pads; and a threading tap carried on one end of said spindle.

19. In a machine of the character described, a mounting, a swivel-head having pivoted connection to said mounting and capable of adjustment in relation thereto, a support pivotally mounted on said swivel-head, an axially moveable spindle carried by said support, and a threading tap mounted on one end of said spindle.

20. In a machine of the character described, an adjustable swinging support, a rod, carried on one end of said support, a table support and table carried by said rod, and an axially movable threading mechanism mounted on the other end of said support.

Signed at New York, in the county of New York and State of New York, this 23rd day of March, A. D. 1918.

ARTHUR PESTEL.
